COMBINATION VACUUM CAN AND RIM SEALED CAN OPENER

Patrick F. Keeney, Oakland, Calif.

Application December 21, 1953, Serial No. 399,530

6 Claims. (Cl. 30—123)

This invention relates to improvements in means for removing the weakened strip from cans containing vacuum packed foods, and has special reference to an improvement in can openers which permits conventional use of the can opener for cutting out the tops of cans, or removing the weakened strip from a vacuum can, at will.

The typical can containing vacuum packed foods such as coffee, certain juices and other foods, and even photographic films and papers, as also others which are not vacuum packed but have a weakened strip the removal of which opens the can, are provided with a key which is customarily attached to the top or bottom of the can. The use of this type of key is laborious and rather trying, since it is rather difficult to keep the roll on the key and the following portion of the strip in line, and unless so done, the strip is very difficult to remove, and often results in cuts and scratches of the hands or fingers. It also requires that a key be provided with each can since the coil of strip metal cannot readily be removed from the key and could readily result in injury to the person attempting such removal.

My invention eliminates the necessity for these keys, makes removal of the weakened strip easy and safe with no possibility of injury to the person, and also permits quick, easy and safe removal of the wound strip, and is formed as a part of any type of can opener which has a feed wheel and shaft, and means for rotating the shaft and feed wheel for advancing the can for cutting out the top and with which my invention does not interfere.

In describing the invention reference will be had to the accompanying drawings, in which:

Fig. 1 is a side elevation of a can opener showing my invention applied thereto.

Fig. 2 is a front end elevation with a portion of the operating handle broken away.

Fig. 3 is a sectional elevation through the feed wheel hub with my invention incorporated therein.

Fig. 4 shows a modification of the vacuum strip key locking and retracting means.

Fig. 5 is a fragmentary view drawn to an enlarged scale to show the tapered key.

Fig. 6 diagrammatically illustrates the operation of my invention and the added function of the feed wheel.

Fig. 7 shows my invention applied to the conventional hand can opener.

This invention is applicable to any can opener, either wall or hand type, which has a feed wheel for feeding the can to the cutter, which cutter may be of either, the wheel type or blade type, since the type of cutter has no bearing on the operation of this invention.

The can opener illustrated in Fig. 1 is of the wall or table type for which reason the mounting means is not shown. This can opener comprises a base 10 which terminates at the forward end in a hub 11. An arm 12 projects upwardly from this hub and has a cam lever 13 pivoted to the upper end as indicated at 14, this cam lever terminating in a cam 15. A cutter frame 16 has an opening to pass over the arm 12, and which frame is

2

upwardly urged by a compression spring 17, the frame being pivoted to the frame or base 10 as indicated at 18.

The cutter frame has a lateral extension 19 which terminates in a yoke 20 in which the cutter wheel 21 is pivotally mounted.

5 The feed wheel 22 is normally mounted on a solid shaft which has bearing in the hub 11, with an operating element, such as the crank 23 of wing lever 24 fixed on the other end, the crank being standard for wall and table types of can openers, while the wing lever is standard for hand types and operated by the thumb and finger.

10 As will be noted, all feed wheel type can openers operate on the same principle, that of placing the rim of the can over the edge of the feed wheel, then depressing the cutting wheel to cut into the top of the can adjacent to the rim. In the one shown in Fig. 1, the lever 13 is moved up and forward with the cam 15 depressing the cutter frame which depresses the cutter to a point just slightly below the top edge of the feed wheel. Operating the crank advances the can while the cutter cuts the top out of the can. With the usual hand type fragmentarily illustrated in Fig. 7, the cutter and frame are hand held while the wing lever 24 is operated by the other hand.

15 25 My invention changes the feed wheel shaft to a hollow shaft 25 which is merely the standard shaft provided with a bore extending axially therethrough as indicated at 26, the feed wheel 22 being fixed on one end, and the crank 23 or wing lever 24 being fixed on the other end. The crank or wing lever is also modified by forming a slot transversely in one end of the hub as indicated at 27, or an extension 28 having the slot 27 is fixed to the end of the crank or lever hub as indicated at 29, for application to can openers already marketed, thus making 20 30 35 the invention an attachment available to anyone having a can opener.

30 35 A key 30 consisting of a plain rod slotted at one end as indicated at 31 and tapered as indicated at 32, is 40 45 slideable in this axial bore, and has suitable keying and retraction means at its other end such as the crossarm 33 or knob 34.

40 45 When the key is advanced for removing the weakened strip 35, the crossarm 33 is within the slot and thus locks the key to the shaft and crank or wing lever. If a knob 34 is used, this knob is provided with a key 36 to fit in the slot 27, or any other suitable locking means may be employed.

50 55 For removing the weakened strip, the tongue 37 is raised from the side of the can by some suitable implement such as a knife. The can is raised and the tongue moved into the slot 31 and moved inwardly to have the top of the can in contact with the feed wheel. The crank or wing lever is then operated to roll the weakened strip onto the mandrel or slotted portion 38. When the entire strip has been removed, the crossarm 33 or knob 34 is retracted manually, which strips the wound strip off the tapered mandrel.

60 65 Thus, the invention provides a convenient and useful addition to any feed wheel type can opener and which will require no changes other than the substitution of a hollow feed wheel shaft and the application of suitable locking and retracting means for the mandrel, and, neither the can cutter or the strip remover interferes in any manner, one with the other.

65 I claim:
1. A can opener having a feed wheel, a feed wheel shaft, a cutting member mounted for manual adjustment toward and away from said feed wheel, and manually operable means for rotating said shaft at will, a passage 70 formed axially through said shaft, a bearing for said shaft, a key member axially movable and non-rotatable in said shaft, said key member being movable to two

positions in one of which the key member extends outwardly beyond said feed wheel to form a mandrel having a diametric slot formed therein for reception of the tongue of a weakened opening strip on a vacuum can for removal of the strip with the side face of said feed wheel operating as gauge cooperative with the top edge of the rim of the can, and in the other position said key member is retracted within said bearing and feed wheel for operation of said can opener as a can cover removing device for cutting the top from a rim-sealed can through cooperation between the cutter member and the feed wheel, retraction of said key member extracting the key member from the wound strip through cooperation with the side face of said feed wheel.

2. Means for removing the weakened opening strip on a vacuum can comprising a can opener having a feed wheel, a shaft and a bearing for said shaft, a cutting wheel mounted for manual adjustment relative to said feed wheel, manually operable rotating means fixed on one end of said shaft, said feed wheel being fixed on the other end of said shaft, a passage formed axially through said shaft, a key member slidable and non-rotatable in said passage and having a mandrel portion at one end projectable beyond said feed wheel, said mandrel portion having a terminal end and a diametric slot formed inwardly from said terminal end for reception of the free tongue on said strip with said feed wheel operating as a gauge cooperative with the top edge of the can during removal of the strip, means for advancing and retracting said key member at will respectively for the operation of removing a weakened strip, and, for withdrawing said mandrel portion from the coiled strip on the mandrel and clearing the cutting end of the can opener for operation as a normal can opener through cooperation between said cutting wheel and said feed wheel.

3. A structure as defined in claim 2; said manually operable means for advancing and retracting said key member and for maintaining said key member against rotation in said shaft comprising a second diametric slot formed inwardly from the other end of said shaft, and a transverse key means integral with the other end of said key member and including gripping means and slidable in said second diametric slot.

4. A combination selective rim-sealed can opener and vacuum can sealing strip remover comprising, a base having a feed wheel shaft bearing, a cutting wheel support adjustably mounted on said base and having a cutting wheel rotatably mounted thereon, a feed wheel shaft rotatable in said bearing and having a feed wheel fixed on one end in cooperative relation to said cutting wheel and having manual rotating means at the other end, said cutting wheel being movable to a position for cooperation with said feed wheel for cutting the top out of a

can, an axial bore formed through said shaft, a key comprising a key shaft slidable and non-rotatable in said axial bore and terminating at one end in a mandrel having a diametric slot formed therethrough to receive the tongue of a weakened strip on the side of a vacuum can with said feed wheel functioning as a guide and thrust gauge for the top edge of the rim of the can, said key shaft having keying means at its other end for locking said key shaft to said feed wheel shaft, said key shaft being manually accessible for advancing said mandrel for removal of said weakened strips and being retracted through cooperation with the side wall of a rim-sealed can for operation of the can opener for cutting out the top of a rim-sealed can.

15. 5. A combination can opener for selectively cutting the top out of a rim-sealed can and for removing the weakened strip from a vacuum can, comprising a base having a feed wheel shaft bearing having a feed wheel shaft rotatable therein and having a feed wheel fixed at one end and rotating means at the other end, a cutter frame movably supported by said base and having a cutter cooperatively related to said feed wheel for cutting the top out of a rim-sealed can, a key shaft axially slidable and non-rotatable in an axial passage formed through said feed wheel shaft and terminating at one end in a mandrel having a slit formed therein for reception of the free tongue of a weakened strip on the side of a vacuum can with the rim of the vacuum can rotating against the end face of the feed wheel upon rotation of said feed wheel shaft, said key shaft being retracted through cooperation of the side wall of a rim-sealed can to be opened and being accessible for manual projection to tongue cooperative position at will.

6. A can opener having a feed wheel having a feed wheel shaft and operating means for rotation thereof, a cutter operatively related to said feed wheel for cutting the top out of a rim-sealed can, a mandrel axially slidable and non-rotatable in a passage formed axially in said feed wheel shaft and having a diametric slit to receive the free tongue of a weakened strip on a vacuum can with the end face of said feed wheel operating as a gauge cooperative with the top edge of the rim of the vacuum can during removal of the weakened strip through rotation of said feed wheel shaft and being retractable within said feed wheel shaft for operation of the can opener for opening rim-sealed cans.
